UNITED STATES PATENT OFFICE.

JOSEPH UDELL, OF WISCONSIN VETERANS HOME, WISCONSIN.

NECKTIE-HOLDER.

SPECIFICATION forming part of Letters Patent No. 698,588, dated April 29, 1902.

Application filed January 7, 1901. Renewed March 27, 1902. Serial No. 100,296. (No model.)

To all whom it may concern:

Be it known that I, JOSEPH UDELL, a citizen of the United States, residing at Wisconsin Veterans Home, in the county of Waupaca 5 and State of Wisconsin, have invented a new and useful Necktie-Holder, of which the following is a specification.

This invention relates to necktie-fasteners, and has for its object to provide an improved 10 device of this character for securing the body portion of a necktie to the front collar-button of a neckband of a shirt and to facilitate the application and removal of the device from the collar-button. It is furthermore designed 15 to secure a tight and snug fit of the fastener upon the neckband of a shirt, so as to prevent looseness of the fastener and the tie, and also to provide an article which is complete in itself and may be conveniently applied to any 20 made-up necktie without altering or changing the same in any respect whatever.

With these and other objects in view the present invention consists in the combination and arrangement of parts, as will be herein- 25 after more fully described, shown in the accompanying drawings, and particularly pointed out in the appended claim, it being understood that changes in the form, proportion, size, and minor details may be made within 30 the scope of the claims without departing from the spirit or sacrificing any of the advantages of the invention.

In the drawings, Figure 1 is a rear view of the overlapped front ends of a collar having 35 a necktie secured thereto by means of the present invention. Fig. 2 is a transverse sectional view thereof, showing the fastener clamping the collar ends and the neckband of a shirt. Fig. 3 is a detail perspective view 40 of the fastener removed from the necktie.

Like characters of reference designate corresponding parts in all of the figures of the drawings.

Referring to the drawings, 1 designates an 45 ordinary made-up four-in-hand necktie which is secured to an ordinary turned-down collar 2, having the usual collar-button 3, whereby the collar is secured to the front of the shirt-neckband 4. (Shown in Fig. 2 of the drawings.) These parts are common and well known and have been shown to more ade-

quately illustrate the application of the present fastener.

In carrying out the invention there is provided a body portion 5, as best shown in Fig. 55 3, of substantially rectangular shape, preferably formed from a thin sheet of metal, having its opposite ends folded or bent upon its rear side, so as to form the opposite sleeves or eyes 6. The intermediate portion of the 60 plate is provided with a pair of perforations 7 for the reception of the respective prongs of a staple-fastening 8, (shown in Fig. 2,) whereby the plate is secured to the back of the body portion of the necktie, adjacent to 65 the upper end thereof. Also the plate is bowed laterally, so as to conform to the bow of the collar-band. This plate or body portion is designed to support the fastener proper, which is formed from a single length of 70 spring-wire, which is bent midway of its ends into substantially U shape, so as to form the opposite straight shank portions 9, which are rigidly held within the sleeves 6, or, in other words, the end portions of the plate are folded 75 over upon the shanks and secured in any suitable manner, so as to form a rigid connection between the shanks and the back of the plate. The transverse bowed portion of the wire is bent rearwardly and downwardly, so as to form 80 a rearwardly-offset pendent loop 10, which lies at a suitable distance in rear of the plate, so as to snugly embrace the overlapped ends of a collar and the neckband of a shirt. The opposite end portions of the shank are bent up- 85 wardly or inwardly into the spring-jaws 11, which overlap the rear side of the plate and coöperate therewith to form loops having their upper sides open. The free end of each jaw is bent into an eye or loop 12, so as to 90 form a knob upon the extremity of the jaw, and thereby prevent the same from hanging in the collar.

In using the device to secure a necktie to a collar-button the back of the tie is brought 95 up adjacent to the overlapped ends of the collar, so that the loop 5 may be hooked over the said ends of the collar and the neckband of the shirt, after which the necktie is pulled downwardly until the loop 5 snaps under the 100 inner enlarged body of the collar-button and against the under side of the shank there-

of, with the spring-jaws 11 pressing firmly against the outer side of the overlapped portions of the collar, so as to firmly grip the latter and the neckband between the loop and the jaws, thereby preventing looseness of the fastener and the necktie.

It will be understood that the upper portion of the button-engaging loop should be at or below the top edge of the necktie, never above the same, so that it may be entirely covered and concealed from view by the body of the necktie.

When the present fastener is employed, the usual tape or band which commonly extends around the collar may be dispensed with, thereby facilitating the application of the necktie to a turned-down collar.

What is claimed is—

A necktie-holder, formed from a single length of spring-wire, which is folded intermediate of its ends into substantially U shape,

the bend being bent back to lie in a plane at one side of the plane of the opposite intermediate side portion of the wire and form a button-embracing loop, the opposite ends of the wire being bent back upon the same side with the loop, lying at opposite sides of the closed portion thereof, and forming collar-engaging springs located between the planes of the loop and the intermediate side portions of the wire, and a body-plate lying between the intermediate side portions of the wire, and having its opposite ends folded upon said intermediate wire portions, and provided with intermediate means for connection with a necktie.

In testimony that I claim the foregoing as my own I have hereto affixed my signature in the presence of two witnesses.

JOSEPH UDELL.
